US0D1033482S

(12) United States Design Patent (10) Patent No.: US D1,033,482 S
(45) Date of Patent:  *Jul. 2, 2024

(54) DISPLAY SCREEN PORTION WITH ICON

(71) Applicant: THE PNC FINANCIAL SERVICES GROUP, INC., Pittsburgh, PA (US)

(72) Inventors: Jerry Scheller, Moon Township, PA (US); Todd Tkach, Wexford, PA (US)

(73) Assignee: THE PNC FINANCIAL SERVICES GROUP, INC., Pittsburgh, PA (US)

(*) Notice: This patent is subject to a terminal disclaimer.

() Term: 15 Years

(21) Appl. No.: 29/838,931

(22) Filed: May 17, 2022

Related U.S. Application Data

(63) Continuation of application No. 29/652,436, filed on Aug. 13, 2020, now Pat. No. Des. 956,816.
